UNDERGARMENT

Jacob A. Goldfarb, Frankfort, Ky., assignor to
 Union Underwear Company, Inc., Indianapolis,
 Ind., a corporation of Indiana

Application July 2, 1938, Serial No. 217,184

2 Claims. (Cl. 2-224)

This invention relates to an undergarment of that type generally designated as a "short."

A primary object of the invention is to provide a garment with a minimum amount of elastic material about the belt and with the various elements cut and formed in such manner as to give a more or less form fitting garment but still providing freedom of movement, all without an excess of material which would otherwise bunch or gather to cause discomfort.

These and other objects and advantages of the invention will become apparent to those versed in the art in the following description of one particular form of the invention as illustrated more or less diagrammatically in the accompanying drawings, in which

Fig. 1 is a developed plan view of the various elements entering into the garment;

Fig. 2, a rear elevation;

Fig. 3, a side elevation; and

Fig. 4, a front elevation with the leg portions turned upwardly somewhat.

Like characters of reference indicate like parts throughout the several views in the drawings.

The garment consists primarily of the three essential parts, namely the leg forming panels 10 and 11 and the back panel 12. These elements, as will further be described, are attached by their upper ends to a belt, generally designated by the numeral 13, which is comprised of a rear section 14, side elastic inserts 15 and 16, and a front section divided into the two parts 17 and 18. Particular attention is directed to the belt 13 and particularly to the rear section 14 which is cut and formed to have a top line substantially straight but to have its under line curved downwardly from its ends into a central major portion having a substantial depth greatly exceeding the depth of the ends of the section 14 which are sewed to the respective ends of the elastic inserts 15 and 16. This central depth is preferably at least twice that of the ends of the portion 14.

It has been customary to form the front portion of the belt 13, consisting of the section 17 and 18, to drop down to a depth in front greatly exceeding that part of the belt which passes over the hips of the wearer, that portion in this case being the elastic inserts on the respective sides. In this invention, this rear belt section 14 conforms somewhat to the front belt portion. This increasing of the depth of the rear section 14 toward the center of the section is extremely important in that it provides for form fitting about the waist line but by reason

of the arcuate curvature of the lower edge of the section 14, the panel 12, having its upper end cut to conform to that curvature, is sewed thereto centrally to extend downwardly therefrom to provide the necessary fullness for the seat portion 5 of the garment without having to form that panel 12 in two or more parts or without having to provide gathers therein. That is, the fullness is secured by reason of the panel having a curvature of greater radius than that of the depending belt portion as indicated in Fig. 1, and fitting those differently curved portions together to have one follow around in conformity with the other without gathers.

As above indicated, the upper edge of the panel 12 is centrally united to the curved edge of the belt section 14. The right hand edge A of the panel 12 is united with the left hand edge B of the garment portion 11 in the relationship indicated in Fig. 1 by merely bringing those two edges 15 together in overlapping arrangement. Likewise the edge C of the panel 12 is united along the edge D of the portion 10. The upper edges of the two portions 10 and 11 are cut, as indicated in Fig. 1, to follow in each case along the remainder of the lower edge of the belt section 14 and thence along the under edges of the elastic inserts 15 and 16 and then down and around forwardly along the lower edges of the front belt sections 17 and 18.

As indicated in Fig. 1, the lower inner corners of the portions 10 and 11 extend below the lower edge of the panel 12 and are cut to extend diagonally outwardly therefrom to leave the edges E and F respectively. These edges are brought around to be sewed onto the respective edges G and H, as indicated in Fig. 4, and these edge portions G and H are continued on across the lower end of the panel 12 to the center thereof, the lengths of these edges G and H which are 30 attached to the panel 12 edge being that which stop at the notches 19 and 20.

As will be observed in Fig. 1, the edge G is an edge of a slot 21 which is cut back from the extreme outer end of the portion 11 to be parallel with the outer edge.

The outer ends of the portions 10 and 11 are then turned upwardly from the end of the panel 12, Fig. 4, by the edge portions I and K. The exact formation of the front opening of the garment does not enter into the present invention but is described in more detail as a separate invention in an application for U. S. Letters Patent about to be filed.

It is to be noted that the portions 10 and 11 55

are cut to have the weave of the fabric on a bias in relation to that of the panel 12. By dropping the center of the rear belt section 14 down from each end, that lower part of the belt 5 below the narrower portions over the hips may swing outwardly and thus provides in combination with the panel 12 a fullness as is required for comfort without having to gather the top edge of the panel along its attachment with the 10 belt, or without having to provide elastic in that portion of the belt which would be quite annoying in use.

While I have herein shown and described my invention in the one form as is now best known to me, it is obvious that structural changes may 15 be made without departing from the spirit of the invention, and I, therefore, do not desire to be limited to that precise form beyond the limitations as may be imposed by the following claims.

20 I claim:

1. In a woven fabric undergarment of the short type, a pair of like major garment fabric portions forming leg sections, a central back panel having parallel, straight side edges stitched to 25 and along straight edges of said portions and a straight lower end stitched to other edges of said portions, said back panel having a downwardly curving arcuate top edge, a belt having a rear portion longer than the width of said panel with 30 narrow terminal ends and a central intervening inelastic portion of greater depth than the ends, said belt central portion having its lower edge downwardly curving and stitched to and along the upper curved edge of said panel, the curvature of the belt edge extending upwardly on each 35 of said major garment portions, a divided front

belt portion, elastic means uniting the front belt portion and the said terminal ends of the rear belt portion at the sides of the garment, said belt front and rear portions having their top edges in a common plane, whereby end tension on said belt will leave a fullness in the rear therebelow across said panel by reason of outwardly hinging of the lower rear curved portion of the belt. 5

2. In a woven fabric undergarment of the short type, a pair of like major garment fabric 10 portions forming leg sections, a central back panel having parallel, straight side edges stitched to and along straight edges of said portions and a straight lower end stitched to other edges of said portions, said back panel having a downwardly 15 curving arcuate top edge, a belt having a rear portion longer than the width of said panel with narrow terminal ends and a central intervening inelastic portion of greater depth than the ends, said belt central portion having its 20 lower edge downwardly curving and stitched to and along the upper curved edge of said panel, the curvature of the belt edge extending upwardly on each of said major garment portions, a divided front belt portion, elastic means uniting the front belt portion and the said terminal ends of the rear belt portion at the sides of the garment, said belt front and rear portions having their top edges in a common plane, whereby end tension on said belt will leave a fullness in 25 the rear therebelow across said panel by reason of outwardly hinging of the lower rear curved portion of the belt, said major garment portions having their weave on a bias in relation to the weave of said back panel. 30
